UNITED STATES PATENT OFFICE.

JOHN EATON, OF SCHENECTADY, NEW YORK, ASSIGNOR TO GENERAL ELECTRIC COMPANY, A CORPORATION OF NEW YORK.

MOTOR-CONTROL SYSTEM.

1,299,924.

Specification of Letters Patent.

Patented Apr. 8, 1919.

Application filed April 23, 1915, Serial No. 23,339. Renewed January 3, 1919. Serial No. 269,417.

To all whom it may concern:

Be it known that I, JOHN EATON, a subject of the King of Great Britain, residing at Schenectady, county of Schenectady, 5 State of New York, have invented certain new and useful Improvements in Motor-Control Systems, of which the following is a specification.

This invention relates to the electrical 10 operation of machines such as planers and the like and has for its object the provision of means whereby the control of such operation is effected in a reliable and efficient manner.

15 My invention relates more specifically to combined hand and automatic control for electric motors for driving planers and the like. In the operation of electrically driven planers, it is frequently desirable to be able 20 to control the planer from positions remote from the master controller or reversing switch, which is actuated by dogs on the platen of the machine.

Heretofore it has been necessary for the 25 operator to manipulate the reversing switch in order to get the required small movements or "inching" necessary in adjusting the work. To make it possible to operate the reversing switch from both sides of the machine, it is necessary that an operating shaft 30 for the reversing switch extend across the machine and the operator is then limited to these two positions on opposite sides of the machine for manipulation. In large planers 35 this is extremely awkward, since the operator may be machining a large casting which will be of considerable height, so as to make it necessary for him in order to see the work, to climb upon the machine. Under these 40 circumstances, when the operator is adjusting the work, he may have to climb up and down a number of times before he gets the work adjusted. In other words, he cannot see the work while he is manipulating the 45 reversing switch. Another difficulty with this arrangement lies in the fact that the operator has to very carefully consider which way to throw the reversing switch, since if he makes a mistake, it may be very 50 serious. He must also look carefully to the position of the reversing switch before he closes the circuit breaker, since otherwise, it may start off in the wrong direction with disastrous results.

In carrying out my invention, I provide a 55 remote control for a planer or the like which will give the operator complete control at all times from any point around the planer and will also give him means whereby he may know exactly which way the planer will 60 operate when it starts. Generally speaking, this consists of a portable controller which the operator may carry in his hand. The controller comprises a switch for throwing the control from automatic to manual and 65 vice versa and a switch mechanism plainly marked to indicate the "cut" and "return" movement. This control may take the form of push buttons, one of which when pressed will cause the motor to travel in the "cut- 70 ting" direction as long as the button is held in the closed position, but upon releasing the button the machine will stop. Likewise, on pressing the "return" button the reverse operation will be accomplished. The ar- 75 rangement is such that the speed at which the motor operates under the manual control is slower than the normal operating speed, this being accomplished by inserting the starting resistance in the motor circuit. 80 With my arrangement the operator, in any position in which it may be necessary for him to be located in order to inspect the work, may have complete control at hand. He may stop the motor at any time under 85 normal operation by simply throwing the switch which changes from automatic to hand operation. He may then start the motor in either direction at a slow speed and continue it as long as desired. Furthermore 90 the operator need never be concerned about which way the machine will move when he closes the circuit breaker, since the machine cannot be started under any condition until one of the push buttons is operated which 95 will fix the direction of operation.

In one form of my invention, this result is brought about by employing a master controller or reversing switch which is normally biased to return to a neutral or intermediate 100 position. When the master switch is thrown to either position by the planer dogs, it only remains in that position for an instant and then returns to its normal position. This arrangement is made possible by having 105 maintaining circuits for the switches controlled by the master controller, so that after the switches are once operated, they will be

held in closed position by a circuit closed at contacts in the neutral position of the controller.

In my previous application Ser. No. 5 817,365 filed February 7th, 1914, I have described and claimed a system in which there is a manual control for planer operating motors in addition to the automatic control. While in general this is satisfactory, it does 10 not give the complete and safe control which is furnished by my present system. It does not make the manual control entirely independent of the automatic control, since, in changing from manual to automatic 15 it is necessary to throw the master controller to the proper position. In other words, if the operator should be upon the upper part of the machine observing the work under manual control, to change to 20 automatic he must climb down and turn the master controller to the proper position and then quickly climb up again to see that every 25 thing is working satisfactorily. With my present control, he never needs to leave his point of observation nor does he need to be 30 concerned about which way the machine will operate when the circuit breaker is closed.

In the accompanying drawing, I have shown my invention applied to a planer control system of the general type described 35 in the patent to Murphy and Eaton, #1,041,845. In addition to the features disclosed in the said patent, my present system also discloses additional features which are 40 described and claimed in my previous applications above referred to. In order, however, that the operation of my system as a whole may be clear, I shall describe it in its entirety and then point out the features of 45 novelty.

Referring to the drawing which shows diagrammatically one embodiment of my invention, A represents the armature and F the shunt field of an electric motor for driving a planer or the like. The direction of 50 rotation of this motor is controlled by four electromagnetic switches or contactors, two for each direction of rotation. Two of these switches are designated as C and C', respectively for driving in the forward or "cutting" direction, while the other two switches, designated as R and R' respectively, when closed drive the planer in the opposite or "return" direction. These four switches are 55 operated by shunt windings controlled by a master switch S which is biased to assume the "intermediate" or neutral position shown in the drawings of the apparatus hereinafter described. In the drawing the parts are 60 shown in the position they assume when the circuit breaker is open and all parts de-energized. When the line is energized by the closing of the circuit breaker CB and the master controller S is moved so as to 65 engage the finger 10, the windings of the

contactors C and C' are energized in parallel across the line, while with the master switch in the opposite position in contact with the finger 11, the windings of the two contactors R and R' are similarly connected 70 across the line. A starting resistance D is provided for the motor, this resistance being controlled by electromagnetic switch 12 connected so as to close and short circuit the resistance when the counter-electromotive force of the motor rises to a predetermined value. For varying the speed of the motor, I have provided two rheostats, one of which has a resistance r , which is controlled by the arm 13, while the other has 80 a resistance r' controlled by the arm 14. When the motor is started, the switch 12 is open and both of the resistances r and r' are short circuited through the wire 15 and the switch 16, which is spring closed. When 85 the switch 12 closes the switch 16 is opened so as to break the short circuit. With the master switch S in engagement with the finger 10, that is, in the "cutting" position, a portion of the resistance r , the amount of 90 which will depend upon the position of the lever 13, will be connected in the field circuit. When the master switch is moved to the opposite position, the connection to the arm 13 of the rheostat is broken by the 95 closing of the line contactor R so that through the connection at the arm 14 all of the resistance r as well as a portion of the resistance r' will now be in the field circuit.

In order to bring the motor armature to 100 rest quickly, I provide a brake resistance through which the motor armature is short circuited. This brake resistance is divided into two sections BR and B'R'. The purpose of these two sections of resistance is 105 to graduate the dynamic braking current as the field builds up and the motor slows down. For making the dynamic braking connections, I provide the contactor B. This contactor is normally held closed by a 110 spring 17. The winding of this contactor is connected across the armature of the motor so that while the motor is operating the winding tends to close the switch. I have likewise provided a series winding 115 18 which is not energized until the contactor is closed. The five contactors R, R', C, C' and B being arranged as shown in the drawings are provided with four mechanical interlocks, 19, 20, 21, and 22, coöperating 120 with the contactors so as to compel operation in a predetermined manner. The structure of these interlocks forms no part of my invention, but for purposes of illustration, I have shown them pivoted at their middle 125 points and engaged by upwardly projecting stems of two adjacent contactors in the closed position. The operation of these bars is described in the patent above referred to and will be sufficiently clear with- 130

out further description. While the contactor B is closed by a spring, this spring is not sufficiently stiff, to apply any considerable pressure to the contacts, since electromagnetic means are provided for holding the contacts tightly closed.

The line contactors are provided with means for preventing their closure except when the field of the motor is of a predetermined strength. This means consists of resistances 23 and 24 interlocked as herein-after described with the contactor which controls the brake resistance BR. Electromagnetic switch or relay 25 is provided with a winding having one terminal connected with the shunt field F while the other end is connected with the resistance r . The winding of this relay is divided into two halves which are differential or oppose each other, so that when the two halves are energized they neutralize each other and the relay will not close. It is obvious that when the switch 16 is opened, the field current must pass through the two differential portions of the relay winding and through any field resistance which may be in circuit, to the negative side of the line. The relay is therefore inoperative under this condition. When however, the switch 16 is closed the upper half of the relay winding and the resistance are short-circuited so that one half the winding is energized and the relay becomes active. The winding of this relay is so adjusted that when the field current approaches a maximum, that is when the field is nearly full strength, the relay will close, but when the field is weak, the relay will not close even though only one of the windings is energized. When the switch 16 closes, the field resistance is short-circuited so as to strengthen the field, but the field increases gradually due to the inductive effect and until the field current rises to the predetermined value, which is preferable near the maximum, the relay 25 will not operate. When it does operate, it short circuits a section of brake resistance BR. This relay 25 is provided with an interlocking contact 26 connected with the resistance 24 in parallel with the line contactors so that when the relay 25 closes, the circuit of the resistance 24 will be open to permit the line contactors to close.

In order to obtain the same dynamic braking effect when the motor is reversed from high speed as when it is reversed from low speed, I provide means whereby a portion of the braking resistance is short circuited when the motor is dynamically braked from one direction of rotation so that dynamic braking takes place only through a portion of the braking resistance, while when the motor is reversed from the opposite direction of rotation, the braking occurs through the whole braking resistance. For accom-

plishing this purpose, I provide the electromagnetic switch or relay 27 which is so arranged that when the dynamic braking circuit is closed with the motor rotating in the "cutting" or forward direction, it will be closed, but will not be closed when the dynamic braking circuit is closed with the motor rotating in the opposite or "return" direction. To this end the magnetic switch has two windings, one of which, 28, is connected across the line, while the other winding, 29, is connected across the motor armature. These two windings are so proportioned that when the counter-electromotive force of the motor opposes the voltage applied to the winding 28 the switch will remain open, but when the counter-electromotive force is reversed, the relay will close. Furthermore, this relay is arranged to be closed by the potential coil alone so that when the counter-electromotive winding 29 is opposing the winding 28, the switch will not close until the counter electromotive force reaches a low value, that is, when the motor speed drops to a proper point.

In order to immediately stop the motor upon the failure of voltage, I provide a circuit breaker CB which is so arranged as to apply an effective dynamic brake to the motor when the circuit breaker opens. To this end, in the particular form illustrated, I have provided two contacts 32 and 33 which move into and out of engagement with fixed contacts as the circuit breaker closes and opens. The contact 33 engages with three contacts, two of which close a dynamic braking circuit through the motor and a portion of the brake resistance B'R' while the other is connected with the shunt field. The contact 32 engages with two contacts, one of which is connected with the field terminal while the other is connected with the armature circuit during the dynamic braking. When the circuit breaker is opened the armature circuit is immediately closed through a portion of the resistance B'R' and the field circuit is closed across the armature in parallel with the section of braking resistance.

As thus far described, the arrangement is the same as that disclosed in my patent application above referred to. I will now describe my improvements whereby the manual control is effected. As before stated the master controller or reversing switch S is biased to the neutral position shown in the drawing so that it returns to this neutral position as soon as the platen of the planer starts to return. The line contactors for the "cutting" direction C and C' are energized at the contact 10 and the contactors for the "return" direction R and R' are energized at the contact 11. In order to hold the contactors closed when the reversing switch returns to this neutral position, I have provided holding circuits which are

made through the reversing switch in this neutral position. The holding circuit for the contactors C and C' is made at contact 34 through interlock 35 on the contactor 5 C' when the latter closes and the holding circuit for contactors R and R' is made through contact 36 and through interlock 37 on contactor R'. The change of control from automatic to manual and vice versa 10 is effected through the agency of a relay 38 having two bridging contacts 39 and 40. Contact 39 in its upper position makes a holding circuit for the relay winding through a segment 41 on the reversing 15 switch. The contact 40 in its lower position completes the circuit for relay 12, so that when the contact is raised, the relay will open and insert the starting resistance D into the motor armature circuit. In its 20 upper position contact 40 makes the manual control circuit through manual controlled switches 42 and 43. These switches are shown as normally open, switches or push-buttons, those marked 42 being for causing 25 operation in the "cutting" direction while those marked 43 cause the motor to operate in the "return" direction. The circuit through the push buttons 42 is through the interlock 37 on reversing contactor R', and 30 the circuit through push buttons 43 is through the interlock 35 on contactor C'. This makes it necessary that the reversing contactor for one direction of rotation should be closed. A switch mechanism composed of two switches 44 and 45 is provided 35 for changing from automatic to manual control. I have shown this switch mechanism as composed of two switches so that the change may be made from either of two positions although obviously this arrangement 40 is not an essential part of my invention. The arrangement is such that the operation of either one of the switches will stop the motor and throw the control from hand to 45 automatic and vice versa. The operation of either switch may undo what has been accomplished by the operation of the other switch. One switch is intended to be on each side of the planer so that if for instance 50 the manual control is thrown in by operating a switch on one side of the planer, the manual control can be thrown out and the automatic thrown in by operating the switch on the opposite side of the planer. 55 Or one switch may be located at the master controller and the other be a pendant switch convenient to the operator from the upper part of the machine. The return circuit through the line contactors is through the 60 switches 44 and 45 both actuating and holding circuits returning through these switches to the negative side of the line.

As thus constructed and arranged, the mode of operation of my system is as follows: Assuming switches 44 and 45 in the

position shown in full lines in the drawing and assuming that the reversing switch or controller S has been moved by the dog on the planer into engagement with contact 10, contactors C and C' will be energized from 70 the positive side of the line through resistance 23, thence through the windings of contactors C and C' in parallel, through the interlock 37 on contactor R' to the contact 10 on the master controller, thence through 75 contact 46 back to the negative side of the line through the switches 44 and 45. Resistance 24 is in a parallel circuit with the contactors C and C' and resistance 23, the circuit through this resistance 24 extending 80 through the interlock 26 and back to the negative side of the line through wire 47. These resistances are so adjusted that the contactors C and C' will not close until the parallel circuit through the resistance 24 is 85 open. The field circuit is made from the positive side of the line through the wire 48, wire 49 through the field winding F and the lower winding of the relay 25, wire 15 and switch 16 to the negative side of the 90 line. The relay 25 will therefore close but not until the field has become energized at substantially full strength. The closing of the main contacts of the relay 25 has no effect but the opening of the interlock 26 95 opens the circuit of the parallel resistance 24 and causes contactors C and C' to close. The line contactors therefore do not close until the field has reached substantially full strength. The relay 27 will also close since 100 its lower winding 28 is connected across the line and the winding 29 which has a counter-electromotive force coil gradually becomes energized in a direction to assist winding 28. Contactors C and C' as well as relay 105 25 and relay 27 are now closed and the armature circuit of the motor is therefore closed through the contacts of contactors C and C' and resistance D. The motor will now 110 start in the cutting direction and as the armature speeds up contactor 12 will close and short circuit the resistance D of the armature circuit. The closing of this contactor 12 causes a portion of the resistance 115 r to be inserted in the field circuit of the motor, the field circuit now being through the two windings of relay 25. This causes the motor to speed up due to the insertion of the resistance r in the field circuit and causes the relay 25 to open. The motor now 120 runs at full speed in the "cutting" direction. When the end of the stroke is reached, the master switch is thrown over into engagement with the finger 11, thereby de-energizing the contactors C and C' and energizing contactors R and R'. Brake contactor B thereupon closes thereby closing the dynamic brake circuit through the motor and the brake resistance BR, causing the contactor 27 to close by reason of the fact 125 130

that the counter electromotive force of the motor is in a direction to assist the winding 28 which is across the line. As the field strength comes up the relay 25 will close, 5 thereby short circuiting the brake resistance BR and bringing the motor to rest quickly. Upon the closing of relay 25 the circuit of the resistance 24 is opened at the interlock 26 so that the contactors R and R'

10 may close. These contactors can only close therefore when the motor is brought substantially to rest for the additional reason that the contactor R cannot close until the brake contactor is opened. The motor now 15 starts on its return stroke, the operation being the same as before except that the motor is brought up to a higher speed by reason of the fact that the resistance r and a portion of the resistance r' depending upon the position 20 of the lever 14 will be inserted in the field circuit of the motor upon the closing of relay 12. Likewise when the end of the stroke is reached, the operation will be as before but in this case all of the brake resistance BR and B'R' will initially be 25 included in the dynamic brake circuit. This will be the normal mode of operation under automatic conditions.

If now it is decided to operate manually, 30 this may be done by throwing either one of the switches 44 or 45 to its opposite position. This will have the effect of immediately stopping the motor in case it should be running and causing the relay 38 to operate.

35 When the relay 38 closes it completes a holding circuit for self, from the positive side of the line through the winding of the relay, contact 39, segment 41 on the master controller S and back to the negative side of 40 the line. The operation of the relay 38 also deenergizes the relay 12 and inserts the starting resistance in the armature circuit. This is done by the lifting of contact 40 out of engagement with its lower contacts.

45 When the contact 40 engages its upper contacts, a circuit is completed through the push buttons 42 and 43, this circuit being through wire 50, contacts 40, 39, and switches 44 and 45. By the operation of one of the

50 switches 44 or 45, the motor has been stopped. If now one of the push buttons as for instance the "cutting" push button 42 is pressed, the contactors C and C' will be closed, the circuit now passing from the interlock 37 through the push button 42 and wire 50 to the contacts 39 and 40 on the relay

38 in this upper position and through switches 44 and 45. There is also a circuit from contact 39 through the segment 41 on 55 the master switch to the negative side of the line. The motor will therefore start in the "cutting" direction. By opening and closing the push button 42, the motor may be stopped and started at will. The motor will 60 be stopped very quickly under these con-

ditions since both sections of brake resistance are short-circuited. In fact it will stop instantly, this being what is wanted on manual control. When the end of the stroke is reached, the master switch will be operated but the motor will not be stopped since the return circuit of the contactors C and C' will still be made at the switch 44 and 45. Likewise upon pressing one of the push buttons 43, the motor may start in the opposite 70 direction and continue at will. If now it is decided to return to automatic, one of the switches 44 or 45 is operated. Supposing that it is desired that the automatic operation should start in a "return" direction, one 75 of the push buttons 43 is pressed. This causes contactors R and R' to close and make a maintaining circuit for themselves as previously described. The operation will now continue independently of the push button but at slow speed because the relay 12 is open and resistance D in the motor circuit. When the end of the stroke is reached, the relay 38 will be deenergized at the segment 41, the relay 12 will close and the automatic operation will continue in its normal 85 way. With this arrangement upon changing to automatic the operator can fix the direction which he shall go, without reference to the master controller. Furthermore 90 when he closes his circuit breaker, the motor will not start until one of the push buttons is pressed so that there is no danger of starting in the wrong direction.

While I have described my invention as 100 embodied in concrete form and as operating in a specific manner in accordance with the provisions of the patent statutes, it should be understood that I do not limit myself thereto since various modifications thereof 105 will suggest themselves to those skilled in the art without departing from the spirit of my invention, the scope of which is set forth in the annexed claims.

What I claim as new and desire to secure 110 by Letters Patent of the United States, is:—

1. In combination, a reversible electric motor for operating a planer or the like, a reversing switch for the motor automatically operated at the limits of travel of the 115 planer, manually operated switches for controlling the motor for either direction of rotation and means independent of the reversing switch for changing from manual control to automatic control in either direction of rotation as desired.

2. In combination, a reversible electric motor for operating a planer or the like, a reversing switch for the motor automatically operated at the limits of travel of the 120 planer, manually operated switches for controlling the motor in either direction of rotation and connections whereby the direction in which the motor starts under automatic control is controlled by the manual switches. 130

3. In combination, a reversible electric motor for operating a planer or the like, a reversing switch for the motor automatically operated at the limits of travel of the planer, 5 manually operated switches for controlling the motor for either direction of rotation, a switch for changing from manual to automatic control and connections whereby the direction in which the motor starts when the 10 control is changed to automatic is controlled by the manual switches.
4. In combination, a reversible electric motor for operating a planer or the like, a reversing switch for the motor automatically operated at the limits of travel of the planer and biased to an intermediate position during the main portion of the travel, manually 15 operated switches for controlling the motor for either direction of rotation and a switch 20 in circuit with the reversing switch in its neutral position for changing from manual to automatic control.
5. In combination, a reversible electric motor for operating a planer or the like, a reversing switch for the motor automatically operated at the limits of travel of the planer and biased to an intermediate position which it occupies during the main portion of the travel and manually 25 operated switches for controlling the motor for either direction of rotation and starting the motor in either direction for automatic control with the reversing switch in its neutral position.
6. In combination, a reversible electric motor for operating a planer or the like, a reversing switch for the motor automatically operated at the limits of travel of the planer and biased to a neutral position which it occupies during the main portion of the travel, 30 electromagnetic switches for controlling the direction of rotation of the motor having actuating and maintaining circuits made respective in the operated and neutral positions of the reversing switch and manually 35 operated means for controlling the motor in either direction of rotation and starting the motor in either direction for automatic control with the reversing switch in the neutral position.
- 40 7. In combination, a reversible electric motor for operating a planer or the like, a reversing switch for the motor automatically operated at the limits of travel of the planer and biased to an intermediate position during the main portion of the travel, electromagnetic switches for controlling the direction of rotation of the motor having actuating and maintaining circuits made when the reversing switch is operated and maintaining circuits made in the intermediate position of the reversing switch, manually operated switches for controlling the actuating circuit of the electromagnetic switches a relay controlling the 45 circuit through the manual switches and a change over switch having connections for completing the maintaining circuit of the electromagnetic switch in one position and energizing the relay in another position. 100
- 50 In witness whereof, I have hereunto set my hand this 22nd day of April, 1915.
- JOHN EATON.
